DESIGN FOR A CONTAINER FOR TOILET GOODS ARTICLES

Arthur B. Schneider, Chicago, Ill.

Application March 15, 1934, Serial No. 51,064

Term of patent 3½ years

To all whom it may concern:

Be it known, that I, Arthur B. Schneider, a citizen of the United States, residing at Chicago, in the county of Cook and State of Illinois, have invented a new, original, and ornamental Design for a Container for Toilet Goods Articles, of which the following is a specification, reference being had to the accompanying sheet of drawings, forming part thereof.

The single figure shows an elevational view of the container for toilet goods articles constructed in accordance with my design.

I claim:

The ornamental design for a container for toilet goods articles, as shown.

ARTHUR B. SCHNEIDER.
